CONTROL

Harry C. Metzger, Los Angeles, Calif.

Application March 8, 1947, Serial No. 733,392

4 Claims. (Cl. 74—501)

1

This invention relates to improvements in control devices suitable for adjusting and controlling such mechanisms as the throttle valve of a carburetor, the adjustment of the spark, choke, or the like. Such devices frequently are adjusted and controlled by a wire or by a push rod that is axially movable. Heretofore, in effecting the push or pull of such a wire or push rod, the wire has been attached directly to one end of a manually operable lever that is fulcrumed at or near its center. During the adjustment of the lever the end of the lever to which the wire is attached, of necessity passes through an arc and the attached end of the wire consequently must also move through the same arc. It has been found that if the manually operable lever is quickly shifted so as to impart a push to the control wire, such as is occasioned in the course of quickly closing the throttle valve of the carburetor, the wire will be caused to kink due to the fact that a sudden heavy push is applied thereto through the arc. This kinking may hinder the movement of the wire within its protective sheath or casing and in extreme cases the kinking results in the wire breaking so that the throttle valve can no longer be controlled by the manually operable lever.

An object of the present invention is to provide an improved control device for operating a push and pull control wire or rod wherein the end of the wire or rod as the case may be, instead of being connected directly to the manually operable lever, is connected to a guided slide the movement of which is restricted to a straight-line path in direct alignment with the length of the wire or push rod. This slide, in turn, is connected to the manually operable lever by means of a pin and slot connection permitting the end of the lever to swing about its fulcrum through the required arc and have the arcuate movement of its end translated into a straight-line movement of the slide. Means is provided for frictionally holding the lever in any adjusted position to which it may have been set. In this manner, even though the lever is quickly shifted into a shutoff position pushing the wire or push rod with considerable force, danger of kinking the wire is eliminated.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of the improved control device;

Fig. 2 is a vertical section taken substantially upon the line 2—2 upon Fig. 1;

2

Fig. 3 is a partial view in side elevation similar to Fig. 1 but illustrating an alternative form of construction; and

Fig. 4 is a partial view in vertical section similar to Fig. 2 but illustrating an alternative form of construction.

Referring to the accompanying drawings wherein similar reference characters designate similar parts throughout, 10 indicates a suitable supporting plate adapted to be recessed in a dashboard or panel or any other suitable structure suitable for conveniently mounting a control lever 11. This plate adjacent its corners has suitable ears 12 through which screws 13 may be extended to attach a face plate 14 thereto and for mounting the plate 10 and its face plate on the dashboard or panel. Near its center the plate 10 has a boss 15 against which is positioned a fiber washer 16. The lever 11 is positioned 20 against the fiber washer and is fulcrumed on a bolt 17 extending through the lever, washer, and through the boss 15. This lever is swingable about the bolt 17 as a center and through the slot 18 in the face plate. A type of spring 19 is interposed between the head of the bolt 17 and the lever 11. In the form illustrated in Fig. 2, this spring merely consists of a thick washer slotted from opposite sides with slots 20 that preferably extend past the diameter of the washer. In this manner the washer is converted to a structure somewhat S-shaped in cross section functioning as a heavy spring to press the lever 11 firmly against the fiber washer 16 and thus hold the lever in any adjusted position.

In that form of construction illustrated in Fig. 4, a similar spring action is provided by interposing a heavy rubber washer 21 between the head of the bolt and the lever so as to firmly and constantly press the lever against the fiber washer.

At the lower corners of the plate 10 there are bosses 22 and 23 having apertures 24 extending therethrough adapted to receive the closely coiled wire sheath or housing 25 of a control wire 26 sometimes referred to as a Bowden wire. This sheath may be anchored in place by means of a set screw 27. The sheath and wire may extend through either aperture 24 in either of the bosses 22 and 23, depending upon the most convenient arrangement. As illustrated in Fig. 1, the wire extends into the right hand boss 22 but if more convenient the same wire may be extended through the boss 23.

A straight slot 28 is milled or otherwise formed in the plate 10 in direct alignment with the passages 24 through the bosses so as to be in direct alignment with the wire 26 when the wire is installed. This slot is designed to receive a portion

29 of a slide 30. The portion 29 has parallel top and bottom edges that bear against the top and bottom edges of the slot 28 and the body of the slide 30 is designed to slide against one side face of the plate 19. A longitudinally extending bore 31 is formed through the slide to accommodate the wire 26 from either direction and a set screw 32 extends axially into the slide to anchor the end of the wire 26 in place. This set screw also functions as a pin on the slide 30 that extends through an elongated slot 33 in the bottom of the lever. The top of the lever may be equipped with handles 34 and 35 attached thereto such as by a screw or bolt 36.

It will be appreciated from the above described construction that when the lever is swung about its pivot pin or bolt 17 as a center, the arcuate swinging movement of its lower end is translated into a straight-line movement of the slide 30 by virtue of the pin and slot connection at 32 and 33 and by virtue of the fact that the slide has its movement guided and restricted by the edges of the straight slot 28. In this manner the slide is required to move through a straight-line path that is in direct alignment with the length of the wire 26. Consequently, even though the lever 11 is suddenly manipulated with considerable force to push the wire 26 such as may be occasioned by suddenly closing a throttle valve, inasmuch as the push imparted to the wire 26 is in a straight-line direction by the slide 30, danger of bowing or kinking the wire 26 is eliminated. When the wire 26 is pulled by reversely operating the lever 11 it will be maintained in any adjusted or set position by reason of the frictional engagement of the various parts.

The form of construction illustrated in Fig. 3 is the same as that above described with the exception that in lieu of using a wire 26 as the control device that is shifted by the slide, a push rod 37 is used which slides freely through either of the apertures or passages 24 in the bosses 22 and 23. In this form of construction the passage 31 in the slide 30 is enlarged to accommodate the anchored end of the push rod which is anchored therein by the set screw 32 in the same manner as previously described. The rod 37 which may be extended through either of the bosses 22 or 23 will be pushed or pulled by the slide in a straight-line direction, thus avoiding frictional resistance to the shifting of the push rod into any of its adjusted positions.

The above described construction is very advantageously employed on boats for controlling the throttle valve of the boat engine. In some boats there are dual engines each equipped with their own carburetors and which are independently operable. In such arrangements, two of the devices herein disclosed may be mounted on a dashboard, panel or other suitable support in side by side relationship so that the levers 11 of both constructions are sufficiently close together to enable them to be adjusted simultaneously, if desired, or independently if it is desired to control one engine independently of the other.

Various changes may be made in the details of construction without departing from the spirit and scope of the invention as defined by the appended claims.

I claim:

1. A control including a support, there being a straight slot in the support, a slide positioned against the side of the support having a portion extending into the slot, a lever pivotally mounted

upon the side of the support and extending over the outer face of the slide, said lever having a pin and slot connection with the slide whereby on swinging the lever the slide may move in the straight slot and be held therein by the lever, the slide being adapted to have a wire or control rod attached thereto, and means at the pivotal connection between the lever and the support for frictionally holding the lever in adjusted position.

2. A control including a support, there being a straight slot in the support, a slide positioned against the side of the support having an enlarged portion straddling the slot and bearing against the portions of the support bounding the slot, and a reduced portion extending into the slot, a lever pivotally mounted upon the side of the support and extending over the outer face of the slide, said lever having a slot adapted to receive another reduced portion of the slide, whereby on swinging the lever the slide may move in the straight slot and be held therein by the lever, said another reduced portion extending through the slot in the lever and protruding out the other side thereof, and means for fastening the control wire or rod to the slide.

3. A control including a support, there being a straight slot in the support, a slide positioned against the side of the support having an enlarged portion straddling the slot and bearing against the portions of the support bounding the slot, and a reduced portion extending into the slot, a lever pivotally mounted upon the side of the support and extending over the outer face of the slide, said lever having a slot adapted to receive another reduced portion of the slide, whereby on swinging the lever the slide may move in the straight slot and be held therein by the lever, said another reduced portion extending through the slot in the lever and protruding out the other side thereof, and means for fastening the control wire or rod to the slide.

4. A control including a support, there being a straight slot in the support, a slide positioned against the side of the support having a portion extending into and fitting between the walls of the slot so as to be guided thereby in a straight-line movement, a lever pivotally mounted upon the side of the support and extending over the outer face of the slide, said lever having a pin and slot connection with the slide whereby on swinging the lever the slide may move in the slot and be held therein by the lever, the slide being adapted to have a wire or control rod attached thereto.

HARRY C. METZGER.
